UNITED STATES PATENT OFFICE.

LEE CALLAHAN, OF SAN DIEGO, CALIFORNIA.

PROCESS OF AND APPARATUS FOR PRODUCING BUILDING-WORK.

946,332.

Specification of Letters Patent. Patented Jan. 11, 1910.

Application filed June 30, 1909. Serial No. 505,221.

To all whom it may concern:

Be it known that I, LEE CALLAHAN, a citizen of the United States, residing at San Diego, in the county of San Diego and State of California, have invented new and useful Improvements in Processes of and Apparatus for Producing Building-Work, of which the following is a specification.

My present invention has to do with buildings constructed of concrete, cement or other plastic material appropriate to the purpose, and more particularly with the production of cornices and other ornamental elements or adjuncts of such buildings.

15 The object of the invention is the provision of a process of and apparatus for producing the said ornamental elements or adjuncts, and this expeditiously and easily, and in such manner that the work is left with a 20 smooth, unbroken and unmarred surface and otherwise in a perfectly finished condition.

With the foregoing in mind, the invention will be fully understood from the following description and claim when the same 25 are considered conjunctively with the accompanying drawings, hereby made a part hereof, in which:

Figure 1 is a perspective view of a mold upon which may be produced a plurality of 30 my novel shell-like forms for use in providing a building with an ornamental cornice in accordance with my invention. Fig. 2 is a perspective view of one of said forms. Fig. 3 is a transverse section showing a form 35 on the mold. Fig. 4 is a fragmentary perspective view illustrating a length of cornice in the production of which a plurality of forms such as shown in Figs. 2 and 3 may be used to advantage.

40 Similar letters of reference designate corresponding parts in all of the views of the drawings.

Precedent to entering into a detailed description of the characteristics and practice of my invention, I would have it distinctly understood that the mold and form illustrated are for use in producing a certain specific product which is also illustrated, by way of example, and that the mold and form 45 may be of any desired configuration according to the character and shape of the plastic work to be produced; experience having demonstrated that in addition to use in the production of ornamental cornices the invention may be advantageously practiced in the production of concrete pilasters, col- 50 umns, pedestals and other elements and adjuncts of buildings constructed of concrete, cement or the like.

In practicing my invention I first make a 60 mold A such as shown in Fig. 1, of wood or other material consonant with its purpose, and on the said mold I produce one or a plurality of shell-like forms B, such as shown in Fig. 2. By "shell-like forms" I 65 mean concavo-convex forms the outer sides of which are of substantially the same configuration as their inner sides or working surfaces, this being advantageous because it renders the forms light in weight and adapts 70 the same to be handled with facility. Although but one form B is illustrated, it will be understood that in the production of a length of work such as shown in Fig. 4, a 75 number of forms B may be and preferably are employed; the said forms being arranged side by side and maintained in position by shoring or other appropriate means. In the best known way of producing the shell-like form B, I cover the mold A with soft soap 80 commingled with a small proportion of kerosene. I then pour plaster of paris, in a thin plastic state, over the soap-covered mold until the mold is thoroughly covered with the plaster of paris coating. I then take burlap 85 that has been previously soaked in plaster of paris, and spread the same over the first plaster of paris coating; the said first coating of plaster of paris being lettered *a* in Fig. 3, and the burlap bearing plaster of 90 paris being lettered *b*. Over the burlap and the plaster of paris carried thereby I pour or otherwise place a second layer or coating of plaster of paris in a plastic state, and this latter layer or coating which is lettered 95 *c* is made of a thickness commensurate with the use to which the form is to be put and the pressure or weight that it is designed to withstand. Then after the form has set for 100 a period of from thirty to forty minutes, the mold A is gently tapped with a hammer or the like, when the mold will fall away from the form and leave the latter in perfect shape for use in the production of the shape that it is desired to produce in concrete, 105 cement or other plastic material suitable for building purposes. It will here be noted that as many of the forms as may be required for the work in hand may be expeditiously and easily produced in succession on the mold in the manner described, 110 and also that the shell-like form is light in

weight so as to adapt it to be conveniently handled, and that the form is possessed of considerable strength and durability, notwithstanding its concavo-convex character, 5 this latter being due in a measure to the burlap bearing plaster of paris and interposed between the inner and outer layers *a* and *c* of the plaster of paris, so that the whole, when the plaster of paris hardens or is set, 10 forms a homogeneous mass containing burlap calculated to serve as a strengthening binder. It will also be noted that during the production of the form, the placing of the burlap soaked with plaster of paris on 15 the first pouring or layer or plaster of paris, serves to hold the second pouring or layer of plaster of paris and to strongly connect the same with the first pouring or layer. I would further have it understood that when 20 deenmed expedient molds for different shapes of work, and forms corresponding to the said molds may be used before any of the forms are used to give shape to concrete, and in fact before the construction of a concrete 25 building is commenced.

When the shell-like form B or a plurality of such forms are properly placed and maintained in position by shoring or other means suitable to the purpose, I coat the 30 surface of the form or forms that are to give shape to the concrete evenly with paraffin or the equivalent thereof, and then the concrete, cement or other material is poured or otherwise placed in the form or forms, and 35 the work is left until the concrete or other plastic material has hardened or set. At this time the form is removed from the work, when it will be found that the paraffin coating referred to will have effectually prevented the concrete, cement or the like from adhering to the working surface 40 of the form, and will also have prevented the plaster of paris in the form from absorbing any of the water and fine particles of cement which are forced to the outer surface of the work when the plastic material constituting the same is tamped or placed under pressure. Consequently it will be understood that when the form or forms referred to are removed, the fine particles of

cement or fine cement will form a smooth and polished surface, and the form or forms will leave the work in a finished state and without stripping, breaking or otherwise marring the work. These practical advantages will be better appreciated when it is remembered that in the use of wood forms for giving shape to concrete and the like, the concrete sets or hardens before the wood becomes wet, and when the wood absorbs the 60 moisture given off by the concrete, the concrete is caused to crack, and is stripped and broken when the wood form is removed.

It will be gathered from the foregoing that by the practice of my invention work 65 of the character defined may be quickly produced with the expenditure of but a minimum amount of effort and with the assurance that when the form or forms are removed, the work will be left in a finished 70 and unmarred state.

I have entered into a detailed description of the present and best known mode of putting my invention into effect in order to impart a full, clear and exact understanding of 75 the process and the apparatus, but it is obvious that in the future practice of the invention such changes or modifications may be made as do not involve departure from the scope of my invention as defined in the 80 claim appended.

Having described my invention, what I claim and desire to secure by Letters-Patent, is:

The process of producing a shell-like 85 form, which comprises pouring plastic plaster of paris on a mold, soaking a binder in plastic plaster of paris and applying the same to the layer of plastic plaster of paris on the mold, and then pouring plastic plaster of paris over the binder bearing plastic plaster of paris.

In testimony whereof I have hereunto set my hand in presence of two subscribing witnesses.

LEE CALLAHAN.
